(57) **CLAIM**

The ornamental design for full face respirator lens outlet ports, as shown and described.

DESCRIPTION

FIG. 1 is a perspective view of a full face respirator lens outlet ports showing the new design;

FIG. 2 is a front elevational view thereof;

FIG. 3 is a left side elevational view thereof, the right side being a mirror image;

FIG. 4 is a rear elevational view thereof;

FIG. 5 is a bottom plan view thereof; and

FIG. 6 is a top plan view thereof;

FIG. 7 is a perspective view of a full face respirator lens outlet ports showing another embodiment of the new design;

FIG. 8 is a front elevational view thereof;

FIG. 9 is a left side elevational view thereof, the right side being a mirror image;

FIG. 10 is a rear elevational view thereof;

FIG. 11 is a bottom plan view thereof; and,

FIG. 12 is a top plan view.

The portions of the article in broken lines are shown for illustrative purposes only and form no part of the claimed design.
